United States Patent Office

Des. 192,408

Patented Mar. 20, 1962

192,408

BRAID OR THE LIKE

Inge Petsche, Old Greenwich, Conn., assignor to The Bar-men Lace Corporation, Stamford, Conn., a corporation of New York

Filed Sept. 19, 1961, Ser. No. 66,755

Term of patent 3½ years

(Cl. D3—32)

FIG. 1 is a plan view of a braid or the like, embodying my new design.

FIG. 2 is a side elevational view thereof.

I claim:

The ornamental design for a braid or the like, substantially as shown.

References Cited in the file of this patent

UNITED STATES PATENTS

D. 90,194	Hicks	June 27, 1933
D. 134,233	Wackerman	Oct. 27, 1942
D. 140,481	Oppenheim	Feb. 27, 1945